**CASING FOR A PHOTOGRAPHIC FLASH LIGHT
SLAVE ATTACHMENT OR SIMILAR ARTICLE**

William R. King, Denver, Colo., assignor to Minneapolis-Honeywell Regulator Company, Minneapolis, Minn., a corporation of Delaware

Application March 18, 1959, Serial No. 55,046

Term of patent 7 years

(Cl. D61—1)

Figure 1 is a front perspective view of a casing for a photographic flash light slave attachment or similar article, showing my new design;

Figure 2 is a rear elevational view;

Figure 3 is a side elevational view, the opposite side being substantially a mirror image thereof; and

Figure 4 is a bottom plan view thereof.

The dominant features of my new design are shown in solid lines in the drawing, the broken line showing of a flash gun and connecting cord being for illustrative purposes only.

I claim:

The ornamental design of a casing for a photographic flash light slave attachment or similar article, substantially as shown and described.
